UNITED STATES PATENT OFFICE.

MICHAEL KELLY, OF NEW YORK, N. Y.

POISON-FEEDING DEVICE.

SPECIFICATION forming part of Letters Patent No. 503,268, dated August 15, 1893.

Application filed March 29, 1893. Serial No. 468,169. (No model.)

To all whom it may concern:

Be it known that I, MICHAEL KELLY, a citizen of the United States, residing in the city and county of New York and State of New York, have invented a certain new and useful Feeding Device, of which the following is a specification.

The device is a masked trough designed to be used with poisoned food or water for the destruction of vermin, as rats, mice and sparrows. It provides for easy access of the creatures for which it is intended, and forbids the access of larger beasts or birds. The form also prevents the larger creatures from seeing the contents.

The accompanying drawings form a part of this specification and represent what I consider the best means of carrying out the invention.

Figure 1 is a general perspective view. Fig. 2 is an end view, and Fig. 3 a front view of the two ends, partially in vertical section. The remaining figures represent modifications. Fig. 4 is a plan view showing the device in an annular form. Fig. 5 is a section on the line 5—5 in Fig. 4. Fig. 6 is a plan view showing an oblong form. Fig. 7 is a section on the line 7—7 in Fig. 6. Fig. 8 is a corresponding section showing a modified form of the head. Fig. 9 is an end view corresponding to Fig. 8.

Similar letters of reference indicate corresponding parts in all the views where they appear.

A is a board of pine or other suitable material, adapted to lie on the ground or floor, and to form a reliable support.

B is a sheet of zinc or other metal, curled as shown, so as to bring the edges approximately together, one edge B' overhanging or standing considerably farther outward than the other.

C are pieces of wood or metal secured just within the ends so as to sustain the sheet metal and constitute therewith a strong and tight case.

D are nails or screws inserted through holes in the sheet metal exterior to the ends C, and securing it in the desired position on the foot A.

The device should be so adjusted that the part B' overhangs at a proper height, al-

lowing sufficient space under it for the desired animals or birds to move in and out while forbidding the access of larger animals or birds.

The device may be made of various sizes for different uses. I have in my experiments made the device thirty (30) inches long, and the main portion two (2) inches radius, allowing the part B' to overhang or extend two inches farther. This device, so fixed on a board as to leave an open space of about two inches in height under the mask, will serve for rats, mice, and the belligerent and destructive sparrows.

The ends C C are each formed with a wing C' adapted to support and properly stiffen the over-hang B' of the sheet metal. The main portion of the opposite edge of the sheet metal is marked B², and is folded so as to form a smooth edge over which the small animals and birds which it is desired to destroy can easily reach to obtain the food within. The edge is left higher adjacent to each end, as indicated by B³. This higher portion extends up to the level of the edge B', and serves to prevent the larger animals or birds from seeing the food, and as a guard to prevent any from reaching inward by any possibility except by crawling under the low over-hung edge B' or the wings C' at the ends.

Modifications may be made without departing from the principle or sacrificing the advantages of the invention. Instead of sheet metal for the part B, and separate pieces of wood for the ends C C, the whole may be made of cast iron molded thin. In such case the foot may be formed integral therewith. I can use various materials. Wood may serve.

I propose as a modification which may have some advantages, to make the whole of cast iron, or crockery, and instead of making the device straight, curving it so that it shall form an endless ring with the over-hang on the outside. Figs. 4 and 5 show such a modification. Other modifications may be made by forming it in a semi-ring, or in two straight parts joined with an angle—V-shaped. With either of these forms, which will be obvious without drawings, it will lie on a floor or on the ground reliably, without feet.

Figs. 6, 7, 8 and 9 show modifications made

in stout sheet metal and in the form of a trough with a hood sufficiently larger held at a proper height and overhanging on allsides. Fig. 7 shows the hood with a hanging lip. Fig. 5 8 shows the hood without such lip. In both forms the hood overhangs so as to forbid the access of the larger creatures, and so as to prevent their seeing the food or water therein. For convenience in filling and cleaning, the 10 hood in each of these latter forms, is made separate and fitted upon posts and secured by removable keys.

The device may be placed where the pests frequent. It should be exposed out of doors 15 only in the country where the sparrows are objectionable, but for rats and mice wherever they are found.

I claim as my invention—

1. The feeding device herein described comprising a trough of imperforate material and

having an overhanging hood projecting forward and downward below the alignment of a longitudinal slot in said trough all substantially as herein specified.

2. The feeding device herein described having a longitudinal opening therein, a foot or support for said trough, a hood or overhang in proximity to said slot, and guards or screens at the extremities of said slot adapted to prevent access to the trough at those points all 25 30 arranged to serve substantially as herein specified.

In testimony that I claim the invention above set forth I affix my signature in presence of two witnesses.

MICHAEL KELLY.
